UNITED STATES PATENT OFFICE

ANTON LUCICH, OF ST. LOUIS, MISSOURI

ELECTRIC SCISSORS

Application filed April 22, 1927. Serial No. 185,891.

The present invention has reference to barbers' scissors, and more particularly to scissors of the motor driven type.

The primary object of the invention is to provide mechanically operated scissors embodying a stationary blade and a movable blade, novel means being provided for exerting a tension on the movable blade to insure the true cutting of the scissors at all times.

10 A further object of the invention is to provide a laterally extended guard or comb removably connected with the body portion of the device to the end that the combing and cutting operation may be accomplished with 15 one hand of the operator.

A still further object of the invention is to provide a device of this character which may be readily and easily cleaned and oiled, to the end that the device may be kept sanitary at all times.

With the foregoing and other objects in view which will appear as the description proceeds, the invention resides in the combination and arrangement of parts and in the 25 details of construction hereinafter described and claimed, it being understood that changes in the precise embodiment of the invention herein disclosed, may be made within the scope of what is claimed, without departing 30 from the spirit of the invention.

Referring to the drawings:

Figure 1 is a side elevational view of a device constructed in accordance with the invention, a portion of the cover being broken 35 away.

Figure 2 is a plan view of the device, the upper portion of the gear housing being shown in section.

Figure 3 is a sectional view taken on line 40 3—3 of Figure 1.

Figure 4 is a sectional view taken through the comb and stationary blade of the device.

Figure 5 is a sectional view taken on line 45 5—5 of Figure 1.

Figure 6 is a fragmental detail view parts thereof being in section and illustrating the manner of securing the comb to the body portion of the device.

50 Referring to the drawings in detail, the

device includes a body portion indicated generally by the reference character 5, the body portion being hollow and formed with a lateral curved extension 6 defining a gear housing for the main gear 7 that is supported on 55 the shaft 8.

This gear receives motion from the worm 9 formed on the shaft 10 which has one end thereof operating in a bearing formed in the bearing block 11 that also forms a part of the body portion. The opposite end of the shaft 10 is enlarged as at 12, and is provided with a bore in its extremity, the bore being of the key-hole type to accommodate one end of the flexible shaft 13 that operates in the bearing 14. This bearing 14 is formed with an opening to accommodate the pin 15 that is passed through an opening in the sleeve 16, which opening also communicates with the opening formed in the extension 17 formed in the 60 body portion. 65

Operating against the spring is a screw 18 positioned in a threaded opening of the extension 17, the screw being designed to tension the spring and cause the pin to be seated in 70 the opening of the bearing to hold the bearing in position. 75

As clearly shown by Figure 2 of the drawings, the body portion is formed with a laterally extended blade 19 which is disposed 80 at an oblique angle with respect to the lower edge of the body portion to the end that the device may be conveniently handled.

Cooperating with the blade 19 is a movable blade 20 formed at one end of the arm 21 which is formed with an opening to receive the pivot pin 22 that extends through the sleeve 23 and has one end positioned in the threaded opening 23' of the body portion, 85 there being provided a leaf spring 24 for contacting with the blade 20 to exert a pressure on the blade 20 to compensate for wear between the blades so that the movable blade 90 will be held in operative relation with the stationary blade 19 at all times. 95

The inner end of the arm 21 is forked as at 25 and positioned around the pin 26 carried by the gear 7, to the end that as the gear is rotated, as by means of the worm 9, shaft 10 and flexible shaft 13, the movable blade 20 100

will be moved vertically setting up a shearing action with the stationary blade 19 to accomplish the purpose of the invention.

Associated with the blades, is a removable guard embodying a comb 27 that extends at an oblique angle with respect to the bar 28 of the guard, to the end that the comb may be moved through the hair, the blades cutting the hair extending beyond the comb.

This guard is provided with an extension 29 that is fitted in an opening formed in the boss 30 that extends from the sides of the body portion, there being provided a set screw 31 extending through the enlargement and contacting with the extension 29 to hold the extension and guard forming a part thereof in its active position with respect to the blades.

As illustrated by Figure 1, the housing has its wall formed with a recess defining a shoulder 32 on which the removable cover 33 rests, the removable cover being secured by means of set screws 34, to the end that the cover may be readily and easily removed and the interior of the device readily cleaned and oiled.

It might be further stated that the cover also bears against the ends of the spring 24, to hold the spring 24 in position.

From the foregoing it will be seen that when power from a suitable motor, is applied to the flexible shaft 13, the shaft 10 will be operated to rotate the gear 7 which in turn will operate the arm 21 and blade 20 carried at one end thereof, so that the device will be moved through the hair to cut or trim the hair.

I claim:

In mechanical scissors, a body portion including a housing, a gear mounted in the housing, bearings in the housing, a shaft having its ends mounted in the bearings and having a worm formed thereon, said worm meshing with the gear to rotate the gear, one end of the housing extending at an oblique angle and providing a stationary blade, a pivoted blade, a pivot pin on which the latter blade is mounted, one end of the pivoted blade extending into the housing, means for transmitting movement of the gear to the pivoted blade, a bowed spring member having its ends fitted in recesses in the housing, the bowed portion of the spring engaging the pivot pin to hold the pin in position, a cover plate for the housing and adapted to engage the spring member to hold the spring member under tension, and a flexible shaft positioned in one end of the first mentioned shaft to transmit movement thereto.

In testimony that I claim the foregoing as my own, I have hereto affixed my signature.

ANTON LUCICH.
